UNITED STATES PATENT OFFICE.

HARRY P. O'DONNELL, OF LUBEC, MAINE, ASSIGNOR TO AMERICAN CAN COMPANY, OF NEW YORK, N. Y., A CORPORATION OF NEW JERSEY.

DRIER AND FEEDING DEVICE FOR COATED OR LITHOGRAPHED SHEETS OR THE LIKE.

1,333,769.

Specification of Letters Patent. Patented Mar. 16, 1920.

Application filed March 9, 1917. Serial No. 153,546.

To all whom it may concern:

Be it known that I, HARRY P. O'DONNELL, a citizen of the United States, residing in Lubec, in the county of Washington and State of Maine, have invented a new and useful Improvement in Driers and Feeding Devices for Coated or Lithographed Sheets or the like, of which the following is a specification.

10 This invention relates in general to driers and feeding means therefor for coated or lithographed sheets or the like.

Prior to my invention it has been generally the custom to locate the drier just beyond the delivery table of a coating or lithographing press. These driers are ordinarily provided with two or more conveyers which move through the heating chamber and which carry the plates to dry the coating.

15 In order that the driers may take up as little space as possible and yet have the desired capacity, the conveyers are provided with racks which carry the plates standing on edge.

20 Prior to my invention it has been generally the custom to transfer the plates from the press to the racks of the drier manually, two attendants being positioned between the two pieces of apparatus, each taking alternate sheets and depositing them in the racks.

25 This manual feeding is objectionable not only because of the wages necessarily paid the two employees but also of the difficulty of preventing the manual handling from marring the sheets or plates. As the sheets are delivered from the press the coating or lithographing is wet and any finger prints upon the plates are permanent.

30 A further objection to this form of handling the plates resides in the fact that both attendants must be always present to insure proper handling.

35 A principal object of the present invention is the provision of a completely automatic, simple and efficient mechanism or device for transferring the coated plates directly from the press to the driers and this without appreciable alteration of the press or driers, and to thus eliminate any handling 40 of the plates or sheets after they have been coated and before they enter the baking oven with the consequent elimination of

the chance of disfiguration of the freshly printed surfaces by the operators' hands.

Other objects and advantages of the invention will be apparent as it is better understood from the following description when considered in connection with the accompanying drawing illustrating a preferred embodiment thereof.

On the drawing,

Figure 1 is a side elevation of a feeding device embodying my present invention and showing also the adjacent parts of the printing press and baking oven or drier;

Fig. 2 is a top plan view of the same;

Fig. 3 is a section taken substantially on the line 3—3 of Fig. 1 and looking in the direction of the arrows;

Fig. 4 is a detail section taken substantially on the line 4—4 of Fig. 1;

Fig. 5 is a view taken substantially on the line 5—5 of Fig. 1;

Fig. 6 is a section on the line 6—6 of Fig. 1 and looking in the direction of the arrows;

Fig. 7 is a section taken substantially on the line 7—7 of Fig. 2; and

Figs. 8 and 9 are partial enlarged elevations showing certain details of construction to be later described.

Referring to the drawings,

The feeding device shown on the drawing is adapted to receive coated or lithographed sheets from a conveyer 1 forming a part of the printing press and receiving the plates from the printing rolls. This conveyer comprises the ordinary delivery chain 2 provided with the usual propelling fingers 3, suitable side guides 5 for maintaining the plates in accurate position being also provided. The conveyer 1 terminates in the ordinary table 4, which is inclined as shown, and the plates slide over it as they are delivered by the conveyer. The support 4 is supported at one end by a bar 6 in turn carried by side legs 7 and 8 constituting the front supports for the automatic feeding device proper. These legs being secured upon suitable bases 9 and 10. The shaft 11 continuously driven from any source of power (not shown) imparts motion through bevel gears 12, 13 to a shaft 14 mounted in bearings 15 and 16 on the legs 7 and 8. These bevel gears are held in mesh by a

spring 17, indicated in Fig. 6. The shaft 14 carries a main driving sprocket 18 (at the left of Fig. 2 and right of Fig. 6), and this main driving sprocket 18 through the agency of a sprocket chain 19 imparts movement to two sprocket wheels 20 and 21. The sprocket wheel 20 is carried by a shaft 22 extending clear across the feeding mechanism and having bearings on the tops of the legs. The shaft 22 also carries a sprocket 23 which engages a drive chain 24 taking over and driving also a sprocket wheel 25 upon a shaft 26 having bearings 27 and 28 which may be attached to the main frame 29 of the baking oven or drier 30. The shaft 26 carries two sprocket wheels for the chains of what may be termed the feed conveyer. One of these sprocket wheels 31 is engaged by the chain 32 which takes over a sprocket wheel 33 upon a shaft 34 mounted in bearings 35 in the leg 8, and the other sprocket wheel 36 at the other side of the feed conveyer engages a similar chain 37 taking over a sprocket 38, the drive at one side being substantially identical with the drive at the other. The two chains 32 and 37 thus move in unison and they are connected at appropriate distances by cross members 39 from which propelling pins or fingers 40 extend outwardly. The bearings 35 are mounted in guides 35' (Fig. 1) and may be held in adjusted position in said guides by any means well known for the purpose.

35 A slotted guide or support 41 is mounted above the upper travel of the feed conveyer and the pins or fingers 40 move through the slots of this support. The support in the present instance consists of a plurality of bars having curved upper faces supported at one end by a cross member 42 attached to legs 7 and 8 respectively, and at the other end by cross member 43 secured to brackets 44 and 45 which also serve to hold up one end 45 of the side guides or guards 46 and 47.

The sprocket 21, already mentioned, and which is driven by the sprocket chain 19, is mounted upon a shaft 48 located well above the upper travel of the feed conveyer, this shaft having bearing brackets 49 and 50 extending up from the side guards 46 and 47. This shaft carries cams 51 and 52, which cams transmit oscillating motion to shifting rods or levers 53, these rods or levers 55 being fulcrumed at 54 and 55 on a cross member 56 supported by the side guards 46 and 47 through brackets 57 and 58. The rods 53 are connected with push finger carriers or blocks 61 and 62.

60 These blocks are adapted to slide and reciprocate transversely of the feeding device, being guided in their movement by a bar 63 on which they are fitted. Each block carries a push finger 66, 67, (one of which 65 push fingers is shown in enlarged elevation

in Figs. 8 and 9). The two push fingers and attendant parts are duplicates and oppositely arranged. Each push finger is set in a recess bound by faces 68 and 69 in which they have a pivotal movement about pivot pins 66', 67'. It will be noted that the faces 69 are vertical and that springs 71 tend to pull the push fingers 66 and 67 toward and into engagement with the faces 69, which is their operative position.

75 The push fingers 66 and 67 carry pins 72, 73, which are adapted to engage guides or bars 77 and 78 to hold the fingers in the position shown in Fig. 8 during the inoperative periods of said fingers. The two bars 80 77 and 78 are pivotally mounted at 79 and 80 on a cross member 74, which is secured to the side guards 46 and 47 by means of brackets 75 and 76. Two posts 83 extend up from the bar 74 and through springs 84 tend to 85 maintain the bars 77 and 78 in the lowered position shown on the drawings and in engagement with the upper face of the bar 74. This arrangement leaves the bars 77 and 78 in substantially horizontal position, the ends 90 81 and 82 being curved downwardly, as shown, to engage the bar 74.

95 The cams 51 and 52 produce continued oscillation of the bars or levers 53 and these in turn cause the blocks or push finger carriers to reciprocate across and above the feed conveyer. The printed plates are delivered in single file arrangement to the center of the conveyer, as may be seen by viewing Fig. 2, and are there picked up by 100 the pins 40 extending between the bars 41. When the plates arrive beneath the reciprocating push fingers they are marshaled into independent files in the present instance being divided into two files, one on each side 105 of the center of the conveyer. Each push finger engages the sides of alternate plates and moves it transversely as it is carried forward by the conveyer. The two push fingers move together, one being always idle in 110 this embodiment of my invention. The idle finger is disposed above the plate being acted upon by the active or operative finger and in order that this idle finger may not contact with the top of the plate to mar the coating, 115 arrangement is provided to hold it elevated. This arrangement consists in the bars 77 and 78 and pins 72 and 73. When each push carrier block and its finger completes an operative stroke, either the pin 72 soon engages 120 the down-turned end of the bar 77 or the pin 73 engages the down-turned end of the bar 78. The respective actions of these pins and bars are identical and I will describe the action with relation to the pin 73 and bar 125 78. As soon as the pin 73 engages the down-turned end of the bar 78, the pin is lifted and the push finger swung about its push pin 67' and into the position occupied by the push finger 66 in this figure. The push 130

finger 67 then stays elevated until the next succeeding plate has been moved to the right, viewing this figure by the push finger 66. The movement of the blocks to each side is 5 greater than that actually needed to position the sheets in their desired file. In other words, viewing Fig. 3, the movement to the left is not quite complete. The travel of the conveyer and the action of the cam 10 with relation thereto is such that each plate passes from under the influence of the push finger somewhat before the push finger carriers have reached the end of their sidewise travel. After the plates have been carried 15 out of engagement with the push fingers, continued movement of the blocks brings the pin 72 or 73, which is riding upon the guide or bar 77 or 78, opposite or above a recess 85, shown in Fig. 2. The elevated pin drops 20 through this recess and permits the finger it controls to assume a vertical position under the action of the appropriate spring 71. In other words, viewing Fig. 3, continued movement to the left of the blocks 61 and 25 62 is accompanied by a breaking of the contact between the plate and push finger 67 and then a movement of the push finger 66 to vertical position. After the pin 72 has thus dropped through the recess 85, it passes under 30 the guide 77 and returns in vertical position ready to engage the side of the next succeeding plate, at which time the push finger 67 will have been moved to inoperative position by the bar 78. After dropping through the 35 slot the pin is preferably in engagement with the plate or cross member 74.

The coated or lithographed plates are thus shifted to the right and left and marshaled into independent files from which they proceed 40 through the continued action of the conveyer and eventually their upper ends encounter a chute or guide 86 which is inclined upwardly from the delivery end of the feed conveyer at a sharp angle. Viewing Fig. 1 45 it will be noted that a drier conveyer 95 passes through a heating chamber indicated in part at 96. The carrier 95 carries racks 88 which are inclined forwardly in the direction of travel of the conveyer. The arrangement 50 of these racks is such that the plates may be closely stacked and yet prevented from having their coated surface come in contact with either the racks or the next adjacent plate. The chute 86 is inclined at 55 about the angle given these racks and the plate slides first up the chute and then back down it so that the rear edge of the plate in the direction of its travel from the conveyer is the first edge to enter between the racks 60 which hold the plate in standing or edge-wise position. The chute is sharply inclined and in order to prevent the plates sliding down it at too great speed, electromagnets 89 are provided to retard the movement,--these 65 magnets being controlled from any suitable

switch 90. The arrangement of this chute very greatly economizes in space from the feed to the drying conveyer and obviates any necessity of guiding the plates into position by their upper or coated faces. 70

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof. 75 80

I claim:

1. A device for feeding coated or lithographed sheets of tin plate or the like comprising, in combination: a conveyer for receiving the coated plates in single file, and a 85 pusher having fingers for engaging the edges of the sheets for marshaling said plates into a plurality of files during the movement of said plates on said conveyer, means for moving said fingers upwardly and downwardly, 90 and means for moving said pusher laterally.

2. A device for feeding coated or lithographed sheets of tin plate or the like comprising, in combination: a conveyer for receiving coated plates in centrally disposed 95 single file, and a pusher having fingers for engaging the edges of the sheets for marshaling predetermined plates into files on each side of the center of said conveyer, means for moving said fingers upwardly and 100 downwardly, and means for moving said pusher laterally.

3. A device for feeding coated or lithographed sheets of tin plate or the like comprising, in combination: a conveyer for receiving the coated plates in single file, and a pusher having fingers for engaging the edges of the sheets for pushing certain plates arranged in regular order with respect to the other plates sidewise into an independent 110 file, means for moving said fingers upwardly and downwardly, and means for moving said pusher laterally. 105

4. A device for feeding coated or lithographed sheets of tin plate or the like to an 115 oven or drier comprising, in combination: a support on which the plates are placed in single file arrangement, and a pusher having fingers for engaging the edges of the sheets for engaging the side edges of the plates to 120 arrange them in proper relation for delivery to said drier, means for moving said fingers upwardly and downwardly, and means for moving said pusher laterally.

5. A device for feeding coated or lithographed sheets of tin plate or the like comprising, in combination: a conveyer having a plurality of spaced propelling elements adapted to engage behind successive plates, a support for said plates while being pro- 125 130

5 pelled by said propelling elements, and a pusher having fingers for engaging the edges of the sheets for sliding said plates transversely of said support while being carried along by said propelling elements, means for moving said fingers upwardly and downwardly, and means for moving said pusher laterally.

6. A device for feeding coated or lithographed sheets of tin plate or the like comprising, in combination: a conveyer having a plurality of longitudinally spaced transverse series of transversely spaced propelling elements adapted to engage behind successive plates, a longitudinally slotted support through which said propelling elements extend for said plates while being propelled by said propelling elements, and a pusher for sliding said plates transversely of said support and along the successive series of propelling elements while being carried along by said propelling elements.

7. A device for feeding coated or lithographed sheets of tin plate or the like comprising, in combination: a conveyer for receiving the plates in single file arrangement, and a pusher for moving certain of said plates sidewise in their movement on said conveyer, said pusher having a finger for engaging a side of a plate in its operative stroke, said finger returning to initial operative position without engagement with the next succeeding plate.

8. A device for feeding coated or lithographed sheets of tin plate or the like comprising, in combination: a conveyer for receiving the plates in single file arrangement, and a pusher for moving certain of said plates sidewise in their movement on said conveyer, said pusher having a finger for engaging a side of a plate in its operative stroke, said finger being moved out of the way of a succeeding plate during the return or inactive movement of said pusher.

45 9. A device for feeding coated or lithographed sheets of tin plate or the like comprising, in combination: a conveyer for receiving the plates in single file arrangement, and a pusher for moving certain of said plates sidewise in their movement on said conveyer, said pusher having a finger for engaging a side of a plate in its operative stroke, said finger being provided with a pin, and guides for engaging said pin on its operative and return strokes, the guide on the operative stroke being lower to permit the pin to engage the side of a plate, and the guide on the return stroke holding the pin out of contact with the next succeeding plate.

60 10. A device for feeding coated or lithographed sheets of tin plate or the like comprising, in combination: a conveyer to which the plates are delivered in single file arrangement, and a pair of push-fingers each

of which is adapted to move certain plates out of said single file arrangement through engagement with the side edges of said plates, and means for lifting said fingers to inoperative positions and out of contact with said plates in their inoperative side movement over the plates.

11. A device for feeding coated or lithographed sheets of tin plate or the like comprising, in combination: a conveyer adapted to receive plates in single file arrangement, and a pair of pivotally mounted, alternately operative push fingers for pushing certain plates sidewise into independent files, said push fingers being movable together, and means for holding one out of contact with said plates while the other is operating.

12. A device for feeding coated or lithographed sheets of tin plate or the like comprising, in combination: a conveyer adapted to receive plates in single file arrangement, push fingers having means to engage under the sheets for moving certain of said plates sidewise into an independent file, and a push pin carrier movable transversely of said conveyer, a lever for moving said carrier, and a cam for moving said lever.

13. A device for feeding coated or lithographed sheets of tin plate or the like comprising, in combination: a conveyer adapted to receive the plates in single file arrangement, a pair of push fingers for moving certain of said plates into independent files sidewise in both directions from said single file, push finger carriers slidably transversely of the conveyer, a pair of levers for moving said carriers, and a pair of cams arranged above said conveyer for actuating said levers.

14. A device for feeding coated or lithographed sheets of tin plate or the like to an oven or drier comprising, in combination: a conveyer for delivering plates, and a chute for receiving said plates, said chute being inclined upwardly from the delivery end of said conveyer so that the plates received by it slide first up the chute and then down it to cause the rear edge of the sheet to be delivered first from said chute, and a conveyer for receiving said plates from the chute and constructed to carry the plates on edge face to face.

15. A device for feeding coated or lithographed sheets of tin plate or the like to an oven or drier comprising, in combination: a conveyer for delivering plates, and a chute for receiving said plates, said chute being inclined upwardly sharply from the delivery end of said conveyer so that the plates received by it slide first up the chute and then down it to cause the rear edge of the sheet to be delivered first from said chute, and means for retarding the downward movement of said plates in said chute, and a conveyer for receiving said plates

from the chute and constructed to carry the plates on edge face to face.

16. A device for feeding coated or lithographed sheets of tin plate or the like to an oven or drier comprising, in combination: a conveyer for delivering plates, and a chute for receiving said plates, said chute being inclined upwardly sharply from the delivery end of said conveyer so that the plates received by it slide first up the chute and then down it to cause the rear edge of the sheet to be delivered first from said chute, and electro-magnetic means for retarding the downward movement of said plates in said chute.

17. The combination of a drier for coated or lithographed sheets of tin plate or the like, and means for feeding said plates thereto comprising: a drier conveyer provided with forwardly movable racks constructed to carry the plates face to face in its operative travel, an inclined feeding conveyer having a delivery end above the operative travel of said rack, and a chute above the conveyer for receiving said plates from said feed conveyer and adjusting their forward edges upward, said chute being arranged to deliver said sheets into said racks.

18. The combination of a drier for coated or lithographed sheets of tin plate or the like, and means for feeding said plates thereto comprising: a conveyer having racks for carrying the plates disposed on edge, a feed conveyer for feeding said plates to said drier and conveying them in reclined position, and a chute above the conveyer for shifting said plates from reclining to edgewise position with their forward edges upward and disposing them in said racks.

19. The combination of a drier for coated or lithographed sheets of tin plate or the like, and means for feeding said plates thereto comprising, in combination: a conveyer having racks adapted to convey the plates standing on edge, and a chute above the conveyer for receiving said plates from said feed conveyer in up-ended position and delivering said plates rear edge first to said drier conveyer in position substantially in the plane of said chute.

20. The combination of a drier for coated or lithographed sheets of tin plate or the like, and means for feeding said plates thereto comprising, in combination: a drying conveyer having conveying racks inclined forwardly in the direction of travel of said conveyer and adapted to receive the plates in up-ended position, a feed conveyer for delivering plates to said drier, and a chute above the conveyer and disposed substantially in the plane of said racks and

adapted to receive the sheets from said feed conveyer and to reverse their direction of movement to cause the rear edge of the sheets to move first into said racks.

21. The combination of a drier for coated or lithographed sheets of tin plate or the like, and means for feeding said plates thereto comprising, in combination: a drying conveyer having conveying racks inclined forwardly in the direction of travel of said conveyer and adapted to receive the plates in up-ended position, a feed conveyer for delivering plates to said drier, and a chute above the conveyer and disposed substantially in the plane of said racks and adapted to receive the sheets from said feed conveyer and to reverse their direction of movement to cause the rear edge of the sheets to move first into said racks, and means for retarding the movement of said sheets into said racks.

22. A device for feeding coated or lithographed sheets or the like, comprising, in combination: a support formed with slat-like longitudinal elements and intermediate slots and of a width sufficient to receive a plurality of longitudinal files of said sheets, a carrier chain near each side of said support, cross members carried by said chains beneath the support and having sheet-propelling means extending up through the slots thereof, a transverse guide above the support, carriers slidable on said guide, cams and connected mechanism for operating said carriers, push fingers pivotally mounted on said carriers each finger adapted to push plates away from the median line of the support while they are being propelled by said sheet-propelling means, one finger operating to push sheets to the right and the other finger operating to push sheets to the left and said fingers operating on alternate sheets, and means for feeding sheets to said support within the scope of said sheet-propelling means.

23. A device for feeding coated sheets or the like, comprising, in combination: a support for the plates, conveyer mechanism having successive transversely arranged series of plate-propelling devices for moving the plates longitudinally along said support, and transversely operating pushing means for moving alternate plates first to one side and then to the other sidewise along the front propelling faces of said devices while they are being advanced by the latter.

Signed in the presence of two subscribing witnesses.
